UNITED STATES PATENT OFFICE

PAUL BOLLINGER, OF WILKINSBURG, PENNSYLVANIA, ASSIGNOR TO WESTINGHOUSE ELECTRIC & MANUFACTURING COMPANY, A CORPORATION OF PENNSYLVANIA

ROCKER-RING STRUCTURE FOR RAILWAY MOTORS

Application filed January 20, 1930. Serial No. 421,929.

My invention relates to improvements in the rocker-ring structure for supporting the brushholders of railway motors of the commutator type and it has particular relation 5 to multipole single-phase commutator railway motors having a large number of brushes spaced closely about the commutator and having only a single restricted opening in the motor frame through which access must 10 be had to all of the brushholders for inspection and maintenance, said access being provided by mounting the brushholders on a rocker-ring which, when the terminal leads have been disconnected, may be rotated so as 15 to bring any desired brushholder opposite the opening in the frame.

In such motors, the brush must be very accurately positioned with respect to the neutral commutator zones of the motor, which 20 creates quite a problem in assembly, particularly when castings have been utilized, as heretofore. Said castings have involved a very large amount of extremely accurate machining, much of which had to be done in 25 very awkward places at a very great expense, which has been made worse by the fact that such castings inevitably have blow holes which frequently are not discovered until nearly all of the machining operations have 30 been completed, resulting in an extremely large loss on account of scrapped finished parts.

According to my invention, I have provided a novel fabricated rocker-ring assembly admirably adapted for quantity production at very small cost, and characterized principally by having brushholder-blocks or supporting members which are held between 40 two separate rocker-ring members and which may be assembled very accurately in a jig, and may be secured in such accurate assembled position by means of holes which are drilled through the rings and blocks in the 45 jig, said holes being then reamed and fitted with tapered bolts, while the parts are still in the jig, thus eliminating fragile castings, expensive welding and unnecessary weight, and thus effecting the necessary accurate assembly, by means which are no more costly

than the boring of holes in parts which are held in a jig.

Further objects of my invention consist in the utilization of a pair of separately machined brushholder-brackets, involving very 55 simple machining operations, secured to each of the above-mentioned brushholder-blocks, each bracket supporting one brushholder; as well as improved means for clamping the rocker ring in its very accurately adjusted operative position which it must have when the motor is in operation, and, at the same time, retaining the commutator cover, which closes the opening in the frame, in such manner that the cover may be secured 60 in position only when the rocker-ring is in its proper adjusted position; and also improved gear means for rotating the rocker-ring, and brass-to-iron bearing means for so supporting the rotatable rocker-ring assembly as to prevent the rusting together of the 65 parts in a fixed non-rotatable position.

With the foregoing and other objects in view, my invention consists in the combinations of parts and methods of construction 70 and assembly hereinafter described and claimed, and illustrated in the accompanying drawings, wherein:

Figure 1 is an elevational view, reduced to about $\frac{1}{8}$ of the actual size, showing the 80 brushholder assembly of one motor of a twin-motor unit embodying my invention, the housing or end-bracket being removed, and the outline of the frame being indicated in dot-and-dash lines,

Fig. 2 is an elevational view, reduced to about $\frac{1}{21}$ of the actual size, showing the entire twin-motor unit with commutator-end housings and commutator covers in place,

Fig. 3 is a section through the rocker-ring and block assembly, reduced to about 90 $\frac{1}{2}$ of its actual size, the section-plane being indicated by the line III-III in Figs. 1 and 4,

Fig. 4 is a bottom plan view of the brushholder block shown in Fig. 3, before being assembled,

Fig. 5 is an end view of the same, with a part broken away,

Fig. 6 is a section through rocker-ring pin-

100

ion, reduced to about $\frac{1}{3}$ of its actual size, the section-plane being indicated by the line VI—VI in Fig. 2,

Fig. 7 is a section through the rocker-ring clamping device and commutator-cover retaining bolt, reduced to about $\frac{1}{3}$ of actual size, the section-plane being indicated by the line VII—VII in Figs. 2 and 8.

Fig. 8 is a sectional view of the apparatus shown in Fig. 7, the section-plane being indicated by the line VIII—VIII in Fig. 7, and

Fig. 9 is a detail view of the shoulder member for engaging the clamp shown in Figs. 7 and 8.

15 The scales hereinabove indicated refer to the original 8" x 13" drawing, which will be still further reduced to $\frac{3}{4}$ of the original size when the printed edition of the drawings is produced for attaching to the printed 20 patent.

As shown in the drawings, my invention is applied to a twin-motor unit 11 consisting of two 12-pole single-phase commutator motors 12 and 13 joined together in a single 25 frame having a semi-cylindrical cradle member 15 which is adapted to fit over one of the axles of a locomotive, the driving connection between the two motors and the driving-wheel axle being effected by means of pinions 30 mounted on the motor shaft at the end remote from the commutator, and engaging a gear on the driving wheel, as indicated in dotted lines in Fig. 2.

The commutator cylinder 21, indicated in 35 broken lines in Fig. 1, is engaged by twelve sets of carbon brushes 22 which are supported by as many brushholders 23 which, in turn, are supported from separate brushholder-brackets 24 which are supported, in 40 pairs, from six brushholder-blocks 25 which constitute an important part of my invention. The six brushholder-blocks 25 are supported between two rocker-rings 26 and 27 which are machined from weldless rolled-steel rings.

45 As shown in Figs. 3, 4 and 5, each of the brushholder-blocks 25 is burned out of a slab of rolled steel, as indicated by the lines marked with the numeral 28 in Fig. 4, to provide a light-weight structure which, however, 50 may also be drop forged, having four portions 29 which are drilled to provide four holes 30 for receiving four supporting pins 31. The pins 31 are pressed into an insulating tube 32 which is capped, at one end, by 55 a protective steel tube 33 which is pressed tightly into one of the holes 30 of the brushholder-block 25. The free end of the pin 31, with projects out of the hole 30, is provided with a porcelain insulator 34 which covers all 60 but a short projecting end of the pin, as indicated by the numeral 35. After the pins 31 have been assembled in the holes 30 of the block 25, these projecting ends 35 of the pins are milled to provide flat sides 36 and 37, as 65 indicated. Each brushholder-block 25 is also

provided with four supporting lugs 39 having machined surfaces 40 which are parallel with the axes of the bores 30 in the block.

66 Six of the blocks 25, after being prepared as just described, are then placed in a suitable jig (not shown) between the two rocker-rings 26 and 27 which bear against the machined end surfaces 40 of the blocks. The blocks are very accurately centered and alined in the positions necessary for them to have in order to support the brushes in the proper places on the commutator, and, while the parts are so held in the jig, holes are drilled directly through the rings 26, 27 and the supporting lugs 39 of the blocks, as indicated in Fig. 3, the holes being then reamed and fitted with tapered bolts 42 which are pressed into place while the parts are still held in the assembling jig. It will be noted that the requirements for accuracy 85 are so great that tapered bolts 42 must be utilized, in order to prevent the possibility of any looseness whatsoever between the parts, and it will be further noted that this very great accuracy of assembly is obtained 90 by the simplest possible machining operations. The tapered bolts 42 are fitted with nuts 43 which are secured by light welding 44 when properly drawn up in place.

With the parts thus assembled, it will be 95 apparent that the insulated pins 31, with their flat sides 36 and 37, provide means, as shown in Fig. 1, for accurately supporting the brushholder brackets 24 which are provided with accurately machined slots 47 for tightly fitting over the flat sides 36 and 37 of the pins 31, said brackets being held in place against the blocks 25 by means of bolts 48, as shown in Fig. 1. It will be noted that each of these brackets 24 is provided with a 100 previously machined lateral surface 49, which makes a certain predetermined angle with the top surface 50 of the bracket. This lateral surface 49 is accurately bored to receive a tap bolt 51 which extends through the 105 supporting flange of the brushholder 23, thereby accurately supporting the brushholder in position.

As shown in Figs. 1, 7 and 8, two insulated cross-connecting rings 53 and 54 are provided and suitably secured to the respective rocker-rings 26 and 27. Each cross-connecting ring is commonly made in two halves (not shown in detail) which are joined together after the ring is put in place around the 110 brushholder-ring assembly. Each of the cross-connecting rings 53 and 54 carries six 115 equally spaced insulated connectors or arms 53' and 54', respectively, which extends down and connect to alternate brushholders 23, as 120 shown in Fig. 1, so that each of the cross-connecting rings 53 and 54 becomes a terminal for six of the brushholders 23.

The armature leads for the motor are brought in from the top, at the point indi- 130

cated at 56 in Fig. 1, and are carried around to the bottoms of the cross-connecting rings 53 and 54, by means of approximately semi-circular connectors 57 secured in a non-rotatable manner to the stator frame of the motor and bolted to the respective cross-connector rings at a point 58 which is accessible through the opening 59, in the bottom of the frame, through which access is had to the 10 brushholders, as shown in Fig. 1. This arrangement is made so that the bolted connection 58 between the semi-circular terminal connectors 57 and the cross-connecting rings 53 and 54, respectively, may be disconnected 15 by reaching through the opening 59 in the frame, after which the rocker-ring assembly may be rotated, as will subsequently be described, to provide access to any one of the brushholders.

20 The rotatable mounting of the rocker-ring assembly is best shown in Figs. 6 and 7, from which it will be understood that the commutator-end of the stator frame of each motor is provided with two spaced steel rings 25 60 and 61, which are welded to the sheet-steel barrel 62 of the frame. The inner ring 61 has a larger inner diameter than the outer ring 60 and is provided with a bronze lining-ring 63 which is expanded into a tight fit with 30 the steel ring 61. After these parts are assembled, the two rings 60 and 63 are bored out to the same diameter, in a single boring operation, an annular shoulder or abutment 64 being left on the bronze ring 63, as indicated in Figures 6 and 7. This boring operation provides the bearing seat in the stator frame for receiving the brushholder rocker-ring assembly.

35 The brushholder rocker-ring assembly is prepared for mounting in the bearing seat just described, by assembling the rocker-ring parts already mentioned, and adding an internal-tooth gear 66 (Fig. 6) which is made of bronze and which is secured to the outer 40 rocker-ring 26 by means of machine screws 67, as shown in Fig. 6. After the machine screws have been tightened in place, they are secured by peening some of the bronze surface-material of the gear 66 into the slots of 45 the screws, after which the lateral face 68 of the gear 66 is machined to provide an accurate predetermined over-all width of the rocker-ring assembly. At this time, also, the outer peripheries of the rocker-rings 26 and 27, and 50 of the gear 66, are all turned to an accurate diameter which is some eight or ten thousandths of an inch less than the diameter of the bearing surface bored in the stator rings 60 and 63, so as to provide a snug sliding fit 55 of four or five mils clearance all around the rocker-ring assembly.

60 It will be noted, from Fig. 6 and the foregoing description, that at no place is there a steel-to-steel fit of the rotatable rocker-ring assembly in its bearing provided in the stator

member. The outer stator ring 60, which is made of steel, engages the bronze gear 66, while the inner bronze cradle-ring 63 of the stator member engages the inner steel rocker-ring 27 of the rocker-ring assembly. This 70 steel-to-bronze bearing assembly is important in preventing the rotating and stationary parts from rusting together, as would be experienced with a steel-to-steel fit of the parts.

75 The internal-tooth gear 66 is rotated by means of a pinion 70, which is carried by the removable commutator-end housing or bracket 71 and is equipped with a square shaft-end 72 to receive a suitable wrench (not shown) for turning the pinion and gear.

80 The entire rocker-ring assembly, after being placed in the stator member, as above described, is very accurately adjusted to its proper angular position, in the factory, and is then locked in said accurately adjusted position by my novel clamping device shown in Figs. 7, 8 and 9. To this end, a shoulder member 74 is prepared, as shown in Fig. 9, having two enlarged abutments 75 and 76 joined by an integral connecting portion 77 of 90 reduced width and thickness.

95 A shoulder member 74 is bolted to the inner face of each of the rocker-rings 26 and 27, as shown in Figs. 7 and 8, in axial alinement with each other, and they are engaged by a clamp 80 (best shown in Fig. 7), having oppositely directed wing members 81 and 82, which are machined to have a close interlocking fit with the notches provided between the thickened shoulders 75 and 76 of the shoulder 100 members 74; and having a radially extending stud 84 which is welded to the clamp 80 and is adapted to extend down through a perforation 85 in the piece of sheet metal which serves as a commutator cover 86 extending 105 over the opening 59 in the stator frame through which access is had to the brushholders and to the rocker-ring assembly. It will be understood that the clamp 80 is readily inserted in place by first turning it slightly 110 sideways, after which its wing members 81 and 82 are straightened out and pulled back down into the grooves between the thickened shoulder members 75 and 76 of the shoulder pieces 74.

115 The thin sheet-metal commutator cover 86 is provided with a large perforation 85 for making a very loose fit with the downwardly projecting stud 84 of the clamp 80. An accurate fit is then provided by means of a thick 120 steel bar 87 that has been previously prepared with a central opening 88 just the size of the stud 84; and this bar is next set in place over the stud and against the sheet-metal commutator cover-plate 86, so that the bar 87 extends across the opening 59 in the stator frame, as shown in Fig. 7. Then, while the rocker-ring assembly is still held, at the factory, in its accurately-adjusted angular position, the cross-bar 87 of the commutator-cover 125

86 is welded to the cover 86, as indicated at 89 in Fig. 8. Registering holes are then drilled in the bar 87 and in the frame 62, respectively, as indicated at 90, 91 and 92, 93 in Fig. 7, using a suitable template (not shown) to assist in the operation, and the holes at each end of the bar are provided with pins 94 which are adapted, thereafter, to ensure the accurate angular positioning of the rocker-ring assembly before the cover-member 86 can be assembled in place, so that it will be impossible to apply a nut 95 to the end of the clamp-stud 84 to close up the motor for operation unless the rocker-ring assembly is in its proper position.

As an aid to bringing the rocker-ring to its proper position, before attempting to assemble the clamp 80 and commutator-cover 86, the stator frame may be provided with a small index piece which is welded to the inner side of the outer ring 60 of the frame, as indicated at 96 in Figs. 7 and 8. This index piece 96 is provided with a triangular notch 97 which is opposite a similar notch 98 on the outer rocker-ring 26 of the rocker-ring assembly, as indicated in Fig. 7, when the parts are in their proper operative positions.

While I have described and illustrated my invention in a preferred form of embodiment, it will be obvious that such description and illustration are merely illustrative, and that various changes and modifications may be made without departing from the spirit of my invention or losing its essential benefits. I desire, therefore, that the appended claims shall be accorded the broadest construction or interpretation consistent with their language, when read in the light of the prior art. For example, the stator frame barrel 62 and the stator-rings 60 and 61, instead of being welded together, may be integral parts of a single barrel having the rings rolled as one part thereof from a single solid piece of steel, and I wish my claims to be understood as embracing this construction, whenever the stator rings are mentioned.

I claim as my invention:

1. A brushholder rocker-ring assembly characterized by having two rocker-rings and a plurality of separate, equally spaced brushholder-supporting blocks, positioning means for independently securing each block in direct contact with said rings in accurate radially and circumferentially spaced position, and brushholders insulatedly carried by said blocks.

2. The invention, as set forth in claim 1, characterized by having a plurality of insulated supporting pins in each block and means for supporting the brushholders from the pins.

3. The invention, as set forth in claim 1, characterized by having two pairs of insulated supporting pins in each block, two oppositely directed brushholder-brackets car-

ried by said two pairs of pins, respectively, and a brushholder carried by each bracket.

4. In combination, a stator-frame of a dynamo-electric machine of the commutator type, said stator-frame having, at its commutator end, a barrel-like member, two spaced rings within the barrel of the stator-frame, the portion of said barrel between said rings being provided with an opening through which access may be had to the brushholders, a commutator-cover for said opening, a removable commutator-end housing for closing the end of said stator-frame, and a brushholder rocker-ring assembly characterized by having two rocker-rings, a plurality of separate, equally spaced brushholder-supporting blocks, said rings and blocks having accurately aligned holes and tapered bolts making a tight metal-to-metal fit in said holes for independently securing said blocks to said rings in accurate radially and circumferentially spaced positions, a plurality of brushholders insulatedly supported from said blocks, and means for rotatably supporting said rocker-ring assembly within said stator-frame rings.

5. The invention, as specified in claim 4, characterized by the fact that said rotatable supporting means comprise slidably contacting concentric rings of dissimilar metals.

6. In combination, a stator-frame of a dynamo-electric machine of the commutator type, said stator-frame having, at its commutator end, a barrel-like member two spaced rings within the barrel of the stator-frame, the portion of said barrel between said rings being provided with an opening through which access may be had to the brushholders, a commutator-cover for said opening, a removable commutator-end housing for closing the end of said stator-frame, and a brushholder rocker-ring assembly characterized by having two rocker-rings journaled in said stator-frame rings and carrying a gear attached to one of the rocker rings, said rocker-ring assembly being removable from the commutator end of said stator-frame without removing said stator rings, means carried by the stator frame for engaging said gear to rotate said rocker-ring assembly, and means for locking said rocker-ring assembly in only one predetermined rotatably adjusted position in said stator frame.

7. The invention, as specified in claim 6, characterized by the fact that said locking means also engages the commutator-cover for retaining it in position only when said rocker-ring assembly is in said predetermined position.

8. The invention, as specified in claim 6, characterized by the fact that said locking means comprises a clamp having a radially extending stud and a pair of laterally extending wings, a notched shoulder member secured to the inner face of each rocker-ring to be engaged by said wings when the rocker-

ring assembly is to be clamped in its predetermined position, said commutator-cover having a hole for receiving said stud and having means for so positioning it on the frame that 5 it can be applied in only one position, and a nut on the end of the stud for holding the parts in position.

9. The invention, as specified in claim 6, characterized by the fact that the gear is an 10 internal-toothed gear, and the means for rotating the same is a pinion carried by the commutator-end housing.

10. The invention, as specified in claim 6, characterized by the fact that journal bearings 15 between the rocker-ring assembly and the stator-rings comprise dissimilar contacting metals.

In testimony whereof, I have hereunto subscribed my name this 11th day of January, 20 1930.

PAUL BOLLINGER.
